UNITED STATES PATENT OFFICE.

EDWARD A. FOY, OF CINCINNATI, OHIO, ASSIGNOR TO WILLIAM F. FOY, OF SAME PLACE.

ORNAMENT FOR CURTAIN-POLES.

SPECIFICATION forming part of Letters Patent No. 349,640, dated September 21, 1886.

Application filed September 24, 1885. Serial No. 178,012. (No model.)

To all whom it may concern:

Be it known that I, EDWARD A. FOY, a citizen of the United States, residing in Cincinnati, in the county of Hamilton and State of Ohio, have invented certain new and useful Improvements in Ornament for Curtain-Poles, of which the following is a specification.

My invention consists in the means employed for attaching such ornaments to curtain-poles.

The silvering, gilding, and coating of glass to produce a reflecting-surface is old, and I make no claim to the same. The interior of these curtain-pole ornaments may be prepared in any of the ordinary methods. It is also old to protect a coated reflecting-surface from the atmosphere by an application of varnish; but from the structure of these ornaments and the necessity of having them inexpensive, such a method of excluding the air would be impracticable. I preferably prepare the interior by pouring in a liquid solution, which is rinsed around, forming a thin coating on the interior. This coating, thin as it is, is then securely protected from the atmosphere and moisture by filling a portion of the neck of the ornament with plaster-of-paris or other suitable substance, which also serves to strengthen the ornament at its point of attachment to the pole, where there is the greatest danger of breakage.

Figure 1 is a side view, partly in section, of my improved curtain-pole knob; Fig. 2, a cross-section through the neck.

A is the glass ornament, which may be made in the shape of a ball, or any other form to suit taste or fancy. B is the curtain-pole. The

silvering, gilding, or coating on the interior is indicated as a , and may be of any color or form. The neck a' is preferably made flaring for a part at least of the distance toward its opening. The neck a' , which is flaring, has one or more longitudinal ribs or lugs, a^s , and, preferably, has circular or other corrugations for more firmly securing the plaster in its place. A suitable substance is dropped into the neck to close the aperture to the ball and protect the coating on the sides of the neck from the moisture of the plaster-of-paris or other suitable substance with which the neck is filled up to about the line a'' . A screw, a^{10} , is embedded in this filling, the head of the screw having one or more lateral projections, a^{11} , which rest against the ribs or lugs a^s , as shown in Figs. 1 and 2, and serve to preserve the rigidity of the screw and prevent it from turning when the ornament is being screwed into the pole. These reflecting-surface glass ornaments are more tasty and beautiful than the metal ornaments heretofore in use, and will retain indefinitely their brilliancy.

I claim—

A glass ornament for curtain-poles coated on its interior so as to produce a reflecting-surface, and having a neck provided with ribs a^s and filled with plaster-of-paris to the line a'' , in combination with screw a^{10} , having projections a^{11} , and embedded in the filling, as and for the purpose set forth.

EDWARD A. FOY.
